Inventor:

William L. Roessner

By Geo. R. Daniels Atty.

UNITED STATES PATENT OFFICE

112,538

DESIGN FOR A FIRE EXTINGUISHING GRENADE

William L. Roessner, Denver, Colo.

Application October 17, 1938, Serial No. 80,486

Term of patent 14 years

To all whom it may concern:

Be it known that I, William L. Roessner, a citizen of the United States of America and a resident of Denver, Denver County, Colorado, have invented a new, original, and ornamental Design for a Fire Extinguishing Grenade, of which the following is a specification, reference being had to the accompanying drawing, forming a part thereof.

Figure 1 is a top plan view of the fire extinguishing grenade showing my new design.

Figure 2 is a side elevation of the same.

I claim:

The ornamental design for a fire extinguishing grenade, substantially as shown.

WILLIAM L. ROESSNER.
